UNITED STATES PATENT OFFICE.

CARL WALTER VOLNEY, OF BOSTON, MASSACHUSETTS.

IMPROVEMENT IN EXPLOSIVE COMPOUNDS.

Specification forming part of Letters Patent No. 157,143, dated November 24, 1874; application filed July 23, 1874.

To all whom it may concern:

Be it known that I, CARL WALTER VOLNEY, of Boston, in the county of Suffolk and State of Massachusetts, have invented a certain Explosive Compound called "Volney's Powder," of which the following is a specification:

The nature of my invention consists in mixing nitrated naphthaline with an oxidizing agent. This nitrated naphthaline is obtained by the action of nitric acid upon naphthaline.

The result of this treatment of naphthaline is a yellow substance, consisting of mono, di, tri, or tetra nitro-naphthaline, in which one or more atoms of nitrogen-tetroxide are substituted for the corresponding number of hydrogen atoms. Strong nitric acid and high temperature will produce the higher nitrated bodies, as di and tri nitro-naphthaline. From weaker acid and lower temperatures mono and di nitro-naphthaline will result.

All these different nitro bodies will form useful explosive compounds when mixed with equivalent quantities of an oxidizing agent, which can supply sufficient oxygen to oxidize the surplus of carbon, more or less oxygen being furnished by the nitrogen-tetroxide of the nitro-naphthalines; and it follows that the higher the naphthaline has been nitrated the less of the oxidizing agent will be needed, but the greater will be the breaking power of the explosive compound.

This quality I make use of to prepare powders of different strength in the following manner:

To prepare an explosive of great breaking power, for the filling of torpedoes, submarine blasting, blasting of hard rock, &c., I treat naphthaline with strong nitro-sulphuric acid (two parts sulphuric acid of 1.84 specific gravity, and one part nitric acid of 1.5 specific gravity) at a temperature of 212° Fahrenheit. One hundred pounds of naphthaline require four hundred pounds of this acid. The reaction is finished in one hour. All the naphthaline is then converted into a yellow crystalline mass, which is thoroughly washed with water, dried, and pulverized. It consists mainly of di and tri nitro-naphthaline, and I

call it, for this purpose, "Nitrated Naphthaline No. I."

A good blasting powder of great breaking power is obtained in thoroughly mixing the following substances: 2.18 pounds nitrated naphthaline No. I, 0.19 pound saltpeter, 0.16 pound sulphur.

To prepare an explosive of less breaking power, which is, therefore, better adapted for military purposes, blasting in soft and fissured rock, as gypsum, limestone, &c., I incorporate one hundred pounds of naphthaline into four hundred pounds of nitric acid of 1.40 specific gravity, leaving these substances in contact for four or five days. The naphthaline is converted into a brown crystalline mass, which is washed with water, dried, and pulverized. It consists mainly of mono nitro-naphthaline, and more or less di nitro-naphthaline. I call it, for this purpose, "Nitrated Naphthaline No. II."

The required explosive compound is formed by mixing thoroughly 1 pound nitrated naphthaline No. II, 3.30 pounds saltpeter, 0.51 pound sulphur.

All these substances can be pulverized, mixed, and treated in the same manner as the substances for and in the manufacture of common blasting or gun powder. Instead of saltpeter, any other nitrate, or any chlorate, as sodium nitrate, potassium chlorate, may be used.

The powders prepared in this manner are of yellow color. Friction or concussion will not ignite or explode them. In unconfined packages, brought in contact with fire, it will ignite and burn, but not explode. Before commencing thus to ignite, the powder will first partially melt, and then burn.

To effect an explosion when desired, caps with mercury fulminate, or a small addition of gun-cotton or nitro-glycerine, must be used. The heat and concussion instantaneously developed by these bodies in their explosions will explode these powders. The same may be used with or without confinement, but the powder No. II should not be used without confinement or tamping.

Their indifference to friction, concussion,

and heat under all circumstances render their handling and transportation safe. Their effective labor is very great.

I claim as my invention—

The explosive compound composed of nitrated napthaline, substantially as described, and an oxidizing agent, prepared in the man-

ner and substantially in the proportions and for the purposes set forth.

CARL W. VOLNEY.
